US00D994650S

(12) **United States Design Patent** (10) **Patent No.:** **US D994,650 S**
Feng (45) **Date of Patent:** **** Aug. 8, 2023**

(54) **USB MICROPHONE**

(71) Applicant: **YARMEE ELECTRONIC TECHNOLOGY CO., LTD.**,
Guangzhou (CN)

(72) Inventor: **Qingmin Feng**, Leizhou (CN)

(73) Assignee: **YARMEE ELECTRONIC TECHNOLOGY CO., LTD.**,
Guangzhou (CN)

(**) Term: **15 Years**

(21) Appl. No.: **29/802,233**

(22) Filed: **Aug. 4, 2021**

(51) **LOC (14) Cl.** **14-01**

(52) **U.S. Cl.** **USPC D14/227**

(58) **Field of Classification Search**

(57) **CLAIM**

The ornamental design for a USB microphone, as shown and described.

DESCRIPTION

FIG. 1 is a perspective view of a USB microphone showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 7 Drawing Sheets
